DIVIDER PANEL FOR A LUNCH BOX OR THE LIKE

James B. Swett, Barrington, R.I., assignor to Dart Industries, Inc., a corporation of Delaware

Original design application Nov. 2, 1966, Ser. No. 4,512.
Divided and this application Mar. 7, 1968, Ser. No.
10,884

Term of patent 14 years

Int. Cl. D9—04; D7—99

U.S. Cl. D44—1

FIG. 3

FIG. 2

FIG. 4

FIGURE 1 is a perspective view showing my new design for a divider panel for a lunch box or the like;

This application is a division of co-pending design application Ser. No. 4,512 filed Nov. 2, 1966, now abandoned.

I claim:

The ornamental design for a divider panel for a lunch box or the like, as shown and described.
